UNITED STATES PATENT OFFICE.

AUGUSTINE C. WEST, OF BOSTON, MASSACHUSETTS.

DESIGN FOR AN OIL OR GAS STOVE.

SPECIFICATION forming part of Design No. 23,456, dated July 10, 1894.

Application filed January 11, 1894. Serial No. 496,542. Term of patent 7 years.

To all whom it may concern:

Be it known that I, AUGUSTINE C. WEST, a citizen of the United States, residing at Boston, in the county of Suffolk, State of Massachusetts, have invented and produced a new and original Design for Oil or Gas Stoves, of which the following is a specification, reference being had to the accompanying drawing, showing a part thereof, in which the figure represents a perspective view of my design.

The leading features of my design consist in a decorated base and top connected by columns having a lamp resting on said base within said columns.

The circular flaring base A has radiating legs b, the edges d of the base between said legs being escalloped, and the flaring portion of said base being provided with a series of openings f. Columns g extend upward from the

base A to the top B and are provided centrally of their length with a cylindrical enlargement h having a series of openings i. The edge k of the top overhangs the columns and is provided with escallops m, the level portions of said top having a series of openings or fret work v. The central portion p of the top is raised and is surmounted by a cone r terminating in a cap q, a knob t being mounted on said cap q. A bail C extends above said top, the handle j thereof forming a double conical spiral.

I claim as my design and desire to secure by Letters Patent—

The design for a lamp stove, substantially as herein shown and described.

AUGUSTINE C. WEST.
